UNITED STATES PATENT OFFICE.

FREDERICK C. SCHAEKEL, OF TOLEDO, OHIO, ASSIGNOR OF ONE-HALF TO HERBERT J. CHITTENDEN, OF TOLEDO, OHIO.

MAUSOLEUM CONSTRUCTION.

1,094,600.

Specification of Letters Patent. Patented Apr. 28, 1914.

Application filed September 8, 1913. Serial No. 788,644.

To all whom it may concern:

Be it known that I, FREDERICK C. SCHAEKEL, a citizen of the United States, and a resident of Toledo, in the county of Lucas and State of Ohio, have invented a certain new and useful Mausoleum Construction; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to the construction of mausoleums, vaults, or the like, of the class having a multiplicity of casket-receiving crypts or cells built therein, and has particular reference to built up slab structures of this type as distinguished from an integral wall construction. In the use of structures of this character it is found that the liquid matter which frequently seeps or drains from bodies reposing therein, especially where death has occurred from dropsy or other diseases in which a surplus of liquid is present in the system, oozes or slowly works through crevices, open joints or cracks in the structure walls and into adjoining or subjacent crypts, and also from the ends thereof into the common area-way customarily provided, thus becoming most offensive and objectionable by reason of the odors emanating therefrom and the liability of conveying diseases.

The object of my invention is to overcome the objections to mausoleums and vault constructions above noted by the provision of improved interlocking connections between the abutting edges or surfaces of adjoining slabs, whereby the seepage of liquid therebetween is prevented and the structure materially strengthened, thus enhancing the practicability and commercial value of such structure.

The invention is fully described in the following specification, and while, in its broader aspect, it is capable of embodiment in numerous forms, a preferred embodiment thereof is illustrated in the accompanying drawings, in which,

Figure 1 is an end elevation of a plurality of crypts in a structure embodying my in-

vention, with a portion in section. Fig. 2 55 is a section on the line α , α in Fig. 1. Fig. 3 is an enlarged detail of a portion of such section, and Fig. 4 is a perspective view of a plurality of floor and side slabs in assembled interengaging relation. 60

Referring to the drawings, 1 designates the common base of a structure of the class described, which may be of solid or sectional construction as desired, and 2 the tiers of crypts or cells disposed above the same. 65 The walls of the several crypts or cells, as built up in the present instance, are shown as comprising side slabs 3, bottom slabs 4, which also form the ceilings of subjacent cells, and removable end slabs 5. The bottom and side slabs are substantially the same length, and each of the bottom slabs 4 is provided at each end portion on its upper and lower sides with one or more, preferably two, successive transversely extending grooves or recesses 6, with the bottom walls of such grooves tapering outwardly from their inner edges, to provide a shoulder 7 at the outer edge of each recess, with the bottom of one groove tapering 80 from the shoulder at the outer edge of the next inwardly disposed groove, as best shown in Fig. 4. The slabs 4 abut at their side edges against adjoining slabs with the grooves 6 at adjacent ends of the slabs in 85 register. Each of the slabs 4 is also provided adjacent to its side edges in the upper and lower surface thereof with longitudinally extending grooves 8, which extend from the transverse groove 6 at one end to 90 the similar grooves at the opposite end of the slab. The grooves 8 are of slightly greater depth than the grooves 6, or, at least, of sufficient depth to provide a shoulder 9 between each end of a groove 8 and 95 the respective grooves 6. The top surface of the base 1 is also provided with grooves 8 in vertical register with respective grooves 8 in the superimposed slabs 4, and is provided at its end portions with transversely extending 100 tapered recesses 6 similar to those of the slabs 4, as shown in Figs. 1 and 2.

Each side slab 3 is provided in its upper and lower edges at the end portions thereof with stepped tapered surfaces 10 105 which are complementary to the grooves 6 of the floor slabs and adapted to seat therein, as indicated in Fig. 4, the upper and lower

sets of said tapered surfaces 10 seating against the lower and upper surfaces 6 of the respective slabs between which the side slabs are disposed. The slabs 3 are also provided in their sides at the end portions thereof with tapered grooves or recesses 6' which correspond in number, longitudinally register with, and are similar in form to the grooves 6 of the bottom slabs. The upper and lower edges of each side slab 3 are formed with spaced parallel longitudinally extending tongues 11 which connect or substantially connect the tapered surfaces 10 disposed on the same edge of the slab. The tongues 11 are intended to seat within the adjoining edge grooves 8 of abutting bottom slabs 4 to tie such abutting sections together or prevent a separation of the joint therebetween, and to shoulder at their ends against the shoulders 9 at the ends of the respective grooves 8 whereby to coöperate with the interengaging tapered surfaces 6 and 10 to prevent relative endwise movements of the bottom and side slab sections. It will be noted that the ends of the edge portions of the slabs 4 disposed without the grooves 8 also form shoulders which abut against shallow shoulders 12 at the ends of the grooves formed by the associated tongues 11.

The provision of the joints above described, in addition to serving as a means for rigidly locking the slab sections against relative movements, also provides joints of a nature to prevent seepage of liquid matter from one cell into a horizontally adjoining cell or into a subjacent cell or cells should the cement which is disposed between the joints become loose. It is evident that in order for liquid to pass from the interior of one cell to the interior of a horizontally adjoining cell, it is necessary for it to flow upward at two points in its course of passage in escaping from the recess or grooves 8 forming the longitudinally extending joints. It is also evident that the liquid in passing from one cell to a lower adjoining cell is required to pass around the adjacent tongue 11 of the upper slab 3, thence down within the joint 13 between the adjoining edges of floor slab sections, and thence upward and around one or the other of the tongues 11 at the upper edges of the lower side slab 3, so that the seepage of liquid from the bottom of one cell to the adjoining cells is rendered practically impossible, due to the congealing nature of the liquid when its free passage is obstructed. With my improved form of interlocking joints the liquid, which does not congeal within the first recess and thus completely dam or stop up the passage therein, will almost invariably congeal in the second recess due to the circuitous upward and downward course which it is required to take

before reaching an adjoining cell. It is also evident that the interengaging of the complementary tapered surfaces 6 and the provision of the shoulders 9 and 12 at the ends of the tongue and groove joints 8-11 prevents the liquids from escaping from a cell lengthwise through the grooves formed by the tongue and groove joints, or should the liquid rise past one or the other of the shoulders 9-12, it would be required, in addition, to rise one or more times in its passage over the successive tapered surfaces 6-10 as the case might be, depending upon whether the joint was at the top or under side of a floor slab.

The removable end slabs or closure members 5 are preferably, but not necessarily, tapered at their edges in opposite relation to the tapered surfaces 6-6', and one is intended to be disposed within each of the surrounding door grooves 6-6', being secured therein by cement 14 which fills the space around the edge of the closure member and necessarily takes the form of a wedge, as best shown in Fig. 3, which wedge prevents a removal of the closure member. The cement wedges 14 are held in position within the groove by coaction with the shoulders 7 of the recesses in the open end portions of the crypts. The inner closure member is intended to abut against a stop shoulder 15 at the inner edge of the innermost recess 6-6'. It is evident that this manner of securing the closure members in position within the crypt openings not only rigidly and firmly secures the members in position but effectually prevents an outward seeping of liquid from the interior of a cell under or around the closure members should cement in the joints become loosened. In that the liquid is required to rise a plurality of times in its upward passage by reason of the shoulders 7-7, thus causing sufficient congealing of the liquid to effectually coöperate with the shoulders to seal the joints against a passage of liquid therethrough.

While the slabs of the structure are shown, in the present instance, as being of reinforced concrete, they may be of stone or other suitable construction, the material of the same not entering into the present invention.

I wish it understood that my invention is not limited to any specific construction or arrangement of the parts except in so far as such limitations are specified in the claims.

Having thus described my invention, what I claim as new, and desire to secure by Letters Patent is,—

1. In a structure of the class described, a plurality of slabs built up to form cells, the side, floor and ceiling slabs having double tongue and groove interlocking joints extending longitudinally thereof and having

- transversely extending interlocking portions at one end thereof which having a damming action with respect to the tongue and groove connections.
- 5 2. In a structure of the class described, a plurality of slabs built up to form cells, the side and floor slabs having tapered interengaging portions at their ends and having multiple tongue and groove connection extending at an angle from said tapered portions, said tapered portions having walls which intercept the free passage of liquid lengthwise through the tongue and groove joints.
- 10 15 3. In a structure of the class described, a plurality of slabs built up to form cells, the floor slabs having transversely disposed tapered grooves at at least one end thereof and having longitudinal grooves adjacent to its side edges, and side slabs having an edge surface adjacent to one end complementary to said transverse grooves to interengage therewith and having longitudinally disposed tongues for fitting into longitudinal grooves of adjoining floor slabs to unite such slabs, said tapered grooves having walls which stand across the longitudinal grooves to dam the same.
- 20 25 4. A cellular structure of the class described built up of slabs, with two floor slabs forming an abutting joint between adjoining cells and with the side wall slab between such cells provided at its lower edge with transversely spaced longitudinally extending tongues for interengaging with the floor slabs, one at either side of abutting edges thereof, to prevent a separation of the joints, said floor and side slabs having transversely disposed interengaging portions forming
- 30 35 40 45 50 55 shoulders which stand in the plane of and intercept the longitudinally-extending interengaging portions to prevent the seepage of liquid therefrom and relative lengthwise movements of the interengaging slabs.
5. A cellular structure of the class described built up of slabs, with two floor slabs forming an abutting joint between adjoining cells and the side wall slab between such cells provided at its lower edge with transversely spaced longitudinally-extending tongues for interengaging with the floor slabs, one at either side of the abutting edges thereof to prevent a separation of the joint, said floor slabs having adjacent ends thereof formed with longitudinally-registering transversely-disposed grooves, the bottoms of which taper outwardly to form successive shoulders which intercept and form dams
- across the portions of the floor slabs with which said tongues interengage and the side slab having edge portions complementary to the transversely grooved portion of the adjoining floor slabs for interengaging therewith.
6. A cellular structure of the class described built up of slabs, with the floor and ceiling slabs of the adjoining cells forming abutting joints therebetween and having their facing surfaces transversely recessed at their ends and longitudinally recessed adjacent to their side edges between the transverse recesses, and with the side slabs provided at their upper and lower edges with transversely-spaced longitudinally-extending tongues for interengaging with the longitudinal grooves of the floor slabs, one at either side of the abutting edges thereof to prevent a separation of the joint, the side slabs having end surfaces for interengaging with the transverse grooves of the floor and ceiling slabs to dam the passage of liquid through the longitudinally-disposed tongue and groove joints and to prevent relative longitudinal movements of the slabs.
7. A mausoleum crypt having successive recesses in the bottom wall of an end opening thereof, the inner wall of the inner recess projecting above the outer walls of the recesses and the bottom of the recesses being outwardly and downwardly tapered, and closure members cemented within said recesses and adapted to be removed therefrom across the outer edge walls of the recesses whereby liquid is required to rise a plurality of times in an outward passage thereof under the closure member.
8. A cellular structure of the class described built up of slabs, with the vertical and horizontal slabs provided at adjacent ends with transversely-extending recesses which register at the ends thereof and having their bottoms tapered, a closure member disposed within said recesses, and cement interposed between the closure member edge and recesses to retain the member therein, said cement forming a wedge which coacts with the recesses to prevent a removal of the closure member therefrom.
- In testimony whereof I have hereunto signed my name to this specification in the presence of two subscribing witnesses.
